J. L. KEGLEY

RIM BAND

Filed Feb. 27, 1922

Fig. 3. J. L. Kegley Inventor

By Chas. C. Brown & Co. Attorneys

UNITED STATES PATENT OFFICE.

JOHN L. KEGLEY, OF SIOUX CITY, IOWA.

RIM BAND.

Application filed February 27, 1922. Serial No. 539,525.

To all whom it may concern:

Be it known that I, JOHN L. KEGLEY, a citizen of the United States, residing at Sioux City, in the county of Woodbury and State of Iowa, have invented a new and useful Rim Band, of which the following is a specification.

This invention aims to provide a novel rim band so constructed that it may be placed readily on a rim, the liner gripping the rim and holding its position on the rim, against shifting.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in longitudinal section, a rim whereon a rim band constructed in accordance with the invention has been mounted; Figure 2 is a top plan of the rim with the band thereon; Figure 3 is a cross section on the line 3—3 of Figure 2; Figure 4 is a detail enlarged from Figure 1.

The rim band forming the subject matter of this application includes a flexible body 1 having an opening 2 for the reception of the valve tube (not shown). The body 1 may be constructed in various ways, but, ordinarily, comprises an inner layer 3 and an outer layer 4, these layers being connected by cementing, vulcanization or otherwise, the body being of the usual cloth stock construction, and being, preferably, inelastic. The outer layer 4 is peeled off the inner layer 3, and is cut away transversely, as at 5, the ends of the outer layer 4 forming tongues 6, of relatively short length, the ends of the inner layer 3 projecting

toward each other beyond the tongues 6, to form extensions 7. Resilient retractile strips 8, which may be made of ordinary elastic, so called, are located side by side and are superposed on the extensions 7 of the layer 3, the ends of the strips 8 being disposed beneath the tongues 6, stitchings 9 or other securing means, connecting the tongues 6, the ends of the strips 8, and the layer 3.

When the rim band is placed about a rim 10, between the clincher flanges 11 thereof, the retractile strips 8 will cause the body 1 to grip the rim closely. The result is, that the liner does not shift its position on the rim, during the mounting of the tire on the rim or whilst the tire is in use, having been mounted on the rim. When all of the slack has been taken out of the body 1, by the retractile strips 8, the ends of the extensions 7 may be cut off, so that they will abut neatly, as indicated at 12.

Having thus described the invention, what is claimed is:

1. A rim band comprising inelastic inner and outer layers, the outer layer being provided with tongues, and the inner layer being provided with extensions prolonged toward each other beyond the tongues, and an elastic strip connected at its ends to the tongues, the extensions constituting means for protecting the strips from contact with a rim.

2. A rim band comprising inelastic inner and outer layers, the outer layer being provided with tongues, and the inner layer being provided with extensions prolonged toward each other beyond the tongues, and an elastic strip having its ends located between the tongues and the extensions and secured to the tongues, the extensions constituting means for protecting the strip from contact with a rim.

In testimony that I claim the foregoing as my own, I have hereto affixed my signature in the presence of two witnesses.

JOHN L. KEGLEY.

Witnesses:

V. K. BERGER,
W. O. WHEELOCK.
